UNITED STATES PATENT OFFICE.

AMANDA I. GROSSMAN, OF CUERO, TEXAS.

HORSE-RELEASER.

SPECIFICATION forming part of Letters Patent No. 600,310, dated March 8, 1898.

Application filed June 16, 1897. Serial No. 641,027. (No model.)

To all whom it may concern:

Be it known that I, AMANDA I. GROSSMAN, a citizen of the United States, residing at Cuero, in the county of De Witt and State of Texas, have invented certain new and useful Improvements in Horse-Releaseers; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to improvements in devices for releasing fractious animals from vehicles, and has for its object the provision of a simply-constructed appliance having such adaptation and possessing advantages in point of efficiency in operation and durability, and added to these the appliance is susceptible of being readily attached to existing vehicles without modification of construction, may be readily manipulated, and in no way interfere with the operation of driving.

The nature of my invention will become clearly apparent from a reading of the following description, which is directed to the details of construction and operation, and in connection with such description attention is called to the accompanying drawings, in which—

Figure 1 is a plan view of the driving-gear of a vehicle with my invention applied thereto, the parts being shown adjusted in position for driving. Fig. 2 is a similar view, but showing the relative position of the parts after the release of the animal has been effected. Fig. 3 is a side elevation, partly in section, of my invention.

Referring to the said drawings by letter, A A denote the shafts or thills of a vehicle, and B is the singletree, to which the traces are removably attached, said singletree being of usual construction with the exception that in each of the ends thereof is a longitudinally-disposed socket b, having a metallic lining, preferably in the nature of an inserted cup-shaped device. Fastened to each end of the singletree is a loop c, provided with a perforation c', which is for a purpose to be presently explained.

Secured to and extending crosswise of the shafts or thills is a plate d, to which is pivotally connected a bar e, the connection being made centrally of the plate and bar by means of a bolt or pin f, which allows of the bar being turned in conjunction with the singletree, to which it is adapted to be connected, as will shortly appear. The bar e carries at each end a sleeve-bearing e', which may be formed integrally therewith or separately and secured thereto, and these bearings are provided in practice as pivotbearings for the vertical portions g' g' of two arms g g, said arms extending forward of the pivotal connections to the ends of the singletree, at which point inward-projecting ends g² g² are provided which are adapted to pass through the perforations in the loops c and to enter the sockets b. From the upper ends of the portions g' extend transversely portions g³ g³, which are flexibly joined at their meeting ends by any suitable connection, such as g⁴. The arms g are connected near their outer ends by a crosswise-extending spring h, which by its action serves to maintain the engagement of the arm ends with the singletree.

In Fig. 1 the parts are shown in the position they assume when the animal is attached to the vehicle, the attachment being made by the engagement of the trace ends with the arm ends g², which latter are passed through the trace-holes. The animal is harnessed to the shafts or thills in a manner which will permit of ready disconnection therefrom, and to effect the release of the animal from the vehicle it is merely necessary that the portions g³ be flexed or moved forwardly by hand, which causes the arms to be moved outwardly to disengage the arm ends g² from the trace-holes. The traces being now unattached the animal is free to disconnect himself from the vehicle. The loops c operate as clearers and insure the disengagement of the traces from the arm ends as the latter are drawn outwardly, as otherwise the engagement might be preserved even after the arm ends have been moved away from the singletree.

My invention, as will appear from the foregoing, is extremely simple both in construction and operation. When the animal is attached to the vehicle, there is no danger of

accidental disconnection, as the spring tends to maintain the locking position of the arms, but when the disengagement is desired it is effected in a very simple and expeditious manner. The appliance is constructed with but few parts, and is hence not liable to disorder. The cost of constructing and applying the invention is comparatively small and when in position the operation of driving is in no way impeded, and the vehicle is not rendered unsightly.

As before stated, the bar is pivotally connected in a manner similar to the attachment of the singletree, and such arrangement allows of the movement of the latter to conform to the motions of the horse when the animal is being driven.

I claim as my invention—

1. The combination with a singletree having socketed ends, of a bar pivoted rearwardly of the singletree, arms pivotally mounted on said bar and having inwardly-projecting ends

for engagement with the singletree-sockets, a spring connecting said arms for maintaining such engagement, and means for moving said arms from engagement with the singletree operated by hand, substantially as described.

2. The combination with a singletree having socketed ends and perforated loops as described, of a bar pivoted to the rear of the singletree and having sleeve-bearings, arms mounted in said bearings and having inwardly-projecting ends adapted for engagement with the singletree-sockets, and having at their other ends a flexible connection, and a spring connecting said arms together, substantially as and for the purpose set forth.

In testimony whereof I affix my signature in presence of two witnesses.

AMANDA I. GROSSMAN.
